GAS-BURNING TORCH

Roy M. Varley, Dallas, Tex.

Application April 20, 1949, Serial No. 88,667

2 Claims. (Cl. 158—99)

1

This invention relates to new and useful improvements in gas burners.

A particular object of the invention is to provide an improved gas burner which will produce high flame temperatures without requiring a supply of air under pressure.

A further object of the invention is to provide an improved gas burner which will operate upon either high or low pressure gas supplies and includes means for drawing combustion air into its interior and thoroughly admixing the same with the combustion gas to provide a flame of relatively high temperature.

Yet another object of the invention is to provide an improved gas burner constructed to employ a high velocity jet of combustion gas and including means for preventing an excessive drop in the pressure of the combustion gas as it passes through the burner.

A further object of the invention is to provide an improved gas burner having a restricted gas jet and an impingement ring so spaced from the jet and of such diameter with relation to said spacing that a cone of gas of normal proportions flowing from the jet will barely impinge in a peripheral fashion upon said impingement ring, whereby thorough agitation and admixing of air and gas upon the outer portions of said cone is effected without the creation of undue turbulence in the central portion thereof.

A particular object of the invention is to provide an improved gas burner having a gas inlet jet, a plurality of primary air ports surrounding the jet, and a plurality of secondary air ports arranged in an annulus and spaced from the jet, the primary air ports directing streams of air across edges of the secondary air ports and causing an aspirating of air through said secondary ports.

An important object of the invention is to provide an improved gas burner having a gas jet and a plurality of air ports surrounding said jet, the axes of the air ports being tangential to the surface of a cone extending from the gas inlet jet, whereby the streams of air passing through said air ports are caused to flow along with the gas entering through the gas inlet jet in a helical path, and admixing of the air and gas is enhanced.

A construction designed to carry out the invention will be hereinafter described together with other features of the invention.

The invention will be more readily understood from a reading of the following specification and by reference to the accompanying drawings, wherein examples of the invention are shown, and wherein:

Fig. 1 is a side elevation of a hand torch incorporating a gas burner constructed in accordance with this invention.

Fig. 2 is a vertical, sectional view of the torch shown in Fig. 1.

Fig. 3 is a front elevation of the torch,

Fig. 4 is a rear elevation of the torch,

Fig. 5 is a horizontal, cross-sectional view of the handle of the torch, taken upon line 5—5 of Fig. 2,

Figs. 6, 7 and 8 are enlarged, vertical, sectional views taken upon the respective lines of Fig. 2,

Fig. 9 is an enlarged view, partly in elevation and partly in section of the burner unit,

Fig. 10 is a greatly enlarged, cross-sectional view taken upon the line 10—10 of Fig. 9,

Figs. 11 and 12 are fragmentary, sectional views taken upon the respective lines of Fig. 9, and

Fig. 13 is a fragmentary view in elevation of the rearward portion of the burner unit.

In the drawings, the numeral 20 designates in general a hand torch having incorporated therein a gas burner following the teachings of this invention. The torch includes a handle 21 formed of a suitable heat insulating material and having a gaseous fuel conduit 22 extending therethrough. A nipple 23 projects from the bottom end of the handle and is connected to the conduit 22 for conducting the fuel gas thereto. A rubber hose (not shown) or any other suitable fuel conductor may thus be connected to the torch by the nipple 23 for supplying fuel gas thereto. At the upper end of the handle, a pipe T 24 is secured to the upper end of the conduit 22, one branch 25 of the T receiving the burner structure, and the other receiving a suitable plug 26 which may be removed for access to the interior or bore of the burner structure should such an operation become desirable.

The burner structure includes a burner unit B and a finned conduit C leading to the unit B. The conduit C comprises a central pipe 27 having integral and closely spaced radial fins 28 formed on its outer surface. A screw-threaded pin 29 is provided at one end of the conduit C for reception in the branch 25 of the pipe T 24, and a screw-threaded box 30 at its opposite end for reception of the burner unit B. An integral cup 31 surrounds the box end of the conduit C and has an outside diameter substantially equal to the outside diameters of the fins 28. For shielding the burner unit, an elongate, thin walled sleeve 32 is pressed over the periphery of the cup 31 and projects forwardly therefrom so as to enclose the rearward end of the burner unit. A plurality of longitudinal air passages 33 are spaced in an annulus about the conduit C and extend longitudinally through the bottom of the cup 31 and through the fins 28 with their axes parallel to the longitudinal axis of the central pipe 27. Air may enter between the fins 28 and flow through the openings 33 to the rearward end

60

of the burner unit whereby an ample supply of air to the burner is insured, but at the same time, the latter is protected against drafts and currents of air which might affect its operation. In addition, the fins 28 function as heat radiating elements and as heat shields to prevent excessive quantities of heat from flowing from the burner unit to the handle structure to discommode the user of the torch. Because the fins receive heat from the burner unit, they, in addition, function as heat exchangers to preheat the inlet air and fuel gas, and to cause it to reach the burner unit in a thoroughly warmed or preheated condition. Some combustion air may also flow through the forward end of sleeve 32, and by reason of its passage over the outside of the burner unit, this air, in a similar fashion, is preheated before being mixed with the fuel gas. It is further to be noted that the rearmost fin, spaced farthest from the burner unit, is imperforate to increase its heat-shielding action.

While the conduit C is important, the principal features of this invention are to be found in the burner unit proper, which is illustrated in detail in Figs. 9 through 13 of the drawings. The burner is applicable to many uses and may be employed both as a stationary and a portable burner. Obviously, the burner may be made in a multitude of sizes and may be employed in a very small hand torch or in various intermediate sizes for portable and stationary heating, and in very large sizes for high capacity furnaces and the like. Therefore, the illustration of the use of the burner in a hand torch is to be viewed as solely for the sake of convenience and explanation, and not as creating any degree of limitation.

An enlarged view of the burner unit B, which may be readily detached from the conduit C by unscrewing from the box 30 of the latter, is shown in Fig. 9. The unit includes an elongate cylindrical housing 34 enclosing a mixing chamber D. The rearward end of the chamber is closed by a substantially transverse wall 35 from which a screw-threaded pin 36 projects rearwardly and axially. The pin 36 is adapted to be received within the box 30 when the burner unit is mounted or connected to the conduit C. An axial bore 37 extends through the pin 36 into the mixing chamber and has pressed therein a gas jet cup 38. A recess 39 is formed in the bottom of the cup 38 and extends within a few thousandths of an inch of the forward wall or outer wall of said cup bottom. Through this very thin section, which may as an example be approximately 0.015 inch thick, a gas inlet jet orifice is drilled, the diameter of said inlet orifice also being of a magnitude of a few thousandths of an inch, for instance 0.035 inch, whereby an extremely small jet of fuel gas may be directed into the interior of the mixing chamber D. The cup 38 seats against an annular shoulder 41 which projects radially inwardly of the forward portion of the bore 37 and functions as a stop for said cup. Since the length of the cup is less than the length of the bore 37, it is obvious that the cup may be adjustably positioned within said bore in order to vary the spacing of the inlet orifice 40 from the rearward portion of the chamber D. As will appear more fully hereinafter, such adjustment is sometimes necessary or desirable to improve the operation of the burner unit under certain conditions or with certain types of fuel supplies.

This burner unit is adapted to be used with

natural gas as commercially supplied, which may be furnished at pressures as low as 3 to 8 inches of water up to several pounds pressure. The burner is also intended for use with low pressure and high pressure gaseous fuels of the butane type, which may also be supplied at very low pressures or at pressures of considerable poundage. The construction of the inlet orifice 40 is of extreme importance in the case of the low pressure fuel supply. It is well known that the pressure drop created in a flowing fluid, or in other words, the resistance to the flow of a fluid, is directly proportional to the length of the conductor through which it must pass. In the present instance, the orifice 40 is cut in a very thin wall, and the resistance offered by the side walls of the orifice to the flow of the fuel gas is practically negligible. There is the usual restriction loss, but the permanent pressure drop is small with the result that gas under pressure as low as 3 to 4 inches of water supplied through the bore 37, are permitted to flow through the orifice 40 in a relatively high speed jet with substantially no loss in velocity being caused by side wall friction within said orifice.

The stream or jet of fuel gas flowing from the orifice 40 into the mixing chamber D, behaves as any high velocity jet or gas flowing into a large open space and tends to fan out into a cone. This cone approaches the side walls of the chamber D at a point spaced forwardly from the orifice 40, and it has been found that such point of close approachment in the case of an unrestricted open jet, is spaced from the orifice a distance equal to approximately twice the diameter of the chamber D.

At this point, an annular impingement ring 42 is positioned. The preferable range of spacing of the ring or restriction from the orifice 40 may be stated to be from $1\frac{1}{2}$ to $2\frac{1}{2}$ times the diameter of the chamber D. The ring 42 has a snug press fit with the interior of the chamber D and has its forward edge flush with the forward end of the cylinder 34, as shown in Fig. 9. As will be explained hereinafter, combustion air is flowing through the chamber D with the jet of fuel gas, and the impingement of the combined flows of fluid upon the rearward edge of the ring 42 creates a marginal turbulence which results in thorough commingling of the combustion mixture. It is important that the ring 42 be of sufficient thickness to create adequate turbulence, and at the same time not be so thick as to unduly impede the progress of the combustion mixture from the burner unit. A desirable ratio between the thickness of the ring 42 and its inside diameter has been found to be 1 to 8. However, it is manifest that a reasonable departure from this ratio may be made without seriously impairing the operation of the burner unit, and the usable ratios may be stated as within the range from 1 to 4 up to 1 to 12. The inner or rearward face 43 of the impingement ring of course forms the inwardly directed, annular shoulder which provides a major portion of the impingement surface. It is preferable that the outer margin of this shoulder surface be adjacent or forwardly beyond the point of intersection of the outer surface or margin of the conical stream of air and fuel gas with the inner surface of the mixing chamber D. If the impingement ring is too close to the orifice 40, there will be no impingement of the stream upon said ring and no turbulence will be created. On the other hand, if the ring is too far from the orifice, an agitation and turbulence

effect will not be achieved, but the ring will merely function as a flow-impeding restriction member in the path of the air-gas mixture.

A combustion chamber E is provided beyond or forwardly of the ring 42, said chamber being enclosed by an annular sleeve 44 having a press fit over the forward end of the sleeve 34. It has been found that actual ignition in the burner unit takes place at a point within the chamber E placed a short distance forwardly of the forward ends or edges of the sleeve 34 and the ring 42. The sleeve 44 thus functions as a shield to protect the point of ignition against air currents and drafts and thus functions to keep the burner ignited. The central portion of the cone of gas jettied from the orifice 40 also functions as a pilot light to maintain ignition since such central portion passes unimpeded through the ring 42, is not subjected to turbulence within the said ring, and has its velocity unreduced by said ring. Of course, the shield or sleeve 44 also functions to focus or direct the flame produced, and for this reason, it is desirable that its inside diameter be kept low so that the stream of fuel gas and air does not undergo excessive enlargement upon exit from the ring 42. It is preferable that the inside diameter of the sleeve 44 not be more than 50 percent greater than the inside diameter of the sleeve 42, but reasonable variations in the latitude of this proportion may be allowed.

That portion of the combustion chamber E immediately forward of the forward ends of the sleeve 34 and the ring 42, constitutes an eddy pocket which is out of the direct blast of gas and air flowing through the ring 42. Combustion continuously taking place in this pocket also serves to maintain ignition of the main stream of the combustion mixture.

The ring 42 likewise has an additional function and beneficial result in preventing backfiring of the flame to the fuel gas orifice 40. Since the stream is restricted within the sleeve 42, its velocity is increased. The proportions of the ring are thus prescribed. The ring must have a bore small enough to maintain the velocity of flow of the combustion mixture in excess of the rate of flame propagation for the fuel mixture being used; the longitudinal length of the ring must be sufficient to maintain the increased velocity over a distance adequate to isolate the combustion and the ignition chambers; and, in opposition, both the contraction or restriction set up by the ring and its length must be held to a minimum to maintain the velocity of the entire gas and air stream. The preferable range of width of the ring shoulder has been set forth hereinabove, and the preferable range for the length of the ring has been found to be from one-quarter of the mixing chamber diameter to equality with said diameter.

Another important feature of the burner unit is the method and means of applying air to form the combustion mixture. A plurality of primary air inlet ports 45 are arranged in an annulus in the wall 35 so as to be in surrounding relation with respect to the orifice 40, and so as to have their axes roughly in parallelism with the axis of said orifice. As shown in Fig. 9, the wall 35 is somewhat concavo-convex in cross-section, and the openings 45, rather than extending exactly parallel to the orifice 40, are faced inwardly toward the axis of the mixing chamber D to provide a plurality of air streams which converge toward the center or axis of said mixing chamber. The structure of the wall 35 is not of im-

portance, but the direction or facing of the openings 45 is. Besides having the inward inclination, each of the openings also have a lateral component in its directional facing as illustrated in Fig. 10. The axes of the openings or ports 45 may thus be described as being tangent to an imaginary sphere or circle of finite diameter located upon the axis of the chamber D and spaced within said chamber from the orifice 40. The plurality of air streams flowing from the plurality of ports 45 thus converge upon the divergent jet of fuel gas flowing from the orifice 40, but such convergence is not in planes normal to the surface of the conical jet of gas, but rather are substantially tangential to said surface. Here again, reasonable degrees of latitude must be allowed and the invention is not to be limited precisely to tangential intersection. Rather, the limitation should be impingement at an angle between tangential intersection and intersection in a plane normal to the gas cone surface. The purpose of this arrangement is to effect a whirling action whereby the air streams and the jet of fuel gas flow in a helix and are thoroughly commingled and mixed for combustion purposes. In practice, this helical path is of constantly-enlarging diameter as it approaches the impingement ring 42, but it is to be kept in mind that the entire body of volume of the gas and air is flowing in such path, and not just the outer portion of the cone of gas and air. Manifestly, the rotational speed of the fuel mixture along the axis of the mixing chamber D will probably be less than the speed within the marginal portions of the cone of gases. However, thorough mixing of the gas and air takes place entirely to the center of the cone whereby efficient and satisfactory combustion is had.

It is further to be noted that other desirable results occur when the incoming streams of air are not directed to a single point at which they intersect and mutually destroy one another to create merely turbulence and random movement. The streams of air intersect the cone of gas at an angle, and tend to continue their movement longitudinally of the mixing chamber D and through the impingement ring 42. The air streams thus inhibit any tendency of the cone of gas to spread laterally to an excessive degree, and aid in maintaining the velocity of the air-gas mixture through the ring 42. The combustion operation and the jetting of the fuel gas into the chamber D cause the air to be drawn in through the ports 45. However, once being drawn in and given an initial velocity, the air streams do not lose their energy or velocity in useless conflict and interference with one another. Rather, the air streams, because of their unique directional arrangement, cooperate and move smoothly toward the ring 42.

For supplying additional air to the fuel mixture, a plurality of secondary air inlet ports 46 are formed in the wall of the sleeve 34 adjacent the rearward end of said sleeve and immediately forward of the primary ports 45. As shown in Figs. 10 and 13, the ports 46 are somewhat larger than the ports 45 and are uniformly spaced or staggered with respect to the latter ports. Thus, each of the ports 45 is positioned substantially intermediate each adjacent pair of the ports 46. The angular facing of the ports 45 provides an additional advantage in this respect since it results in the direction across the inner sides 75 of the ports 46 of the air streams passing

through the ports 45, as illustrated in Fig. 13. The direction of air travel through the ports 45 is seen to be transverse across the openings 46 and at the same time to possess a lateral component inwardly toward the longitudinal center or axis of the chamber D. Further, the directions of movement of said air streams do not pass through the centers or axes of the openings 46, but rather to one side of said axes. The net result of this controlled path of movement of the air streams is to create an enhanced aspirating action through the ports 46 and to cause air to be drawn through said ports in a helical path moving toward the center of the chamber D and simultaneously moving toward the forward open end of said chamber adjacent the combustion chamber E. The three directional components of the paths of movement of the air streams flowing through the ports 45 may be broken down to account for this result. The transverse movement of air streams across the openings 46 achieves the aspirating result and draws air inwardly through said ports 46. The fact that the center or axis of each of the primary air streams passes off center with respect to the secondary air streams results in the helical path of the latter streams. Thirdly, the inward component of the primary air streams toward the axis of the chamber D increases the aspirating effect, tends to move the secondary air streams also toward the mixing chamber axis, and imparts to said secondary air streams a longitudinal component of movement toward the open forward end of the mixing chamber. The utmost use is thus made of the primary air streams to encourage and enhance the flow of the secondary air streams and provide the proper quantities of combustion air for the jet of fuel gas flowing through the orifice 40. The helical flow of the secondary air streams creates additional turbulence for mixing purposes, and the generally inward and forward path of the secondary streams causes the latter to blend into the previously mentioned streams and flow smoothly toward the outlet of the mixing chamber without unduly impairing the forward velocity of said streams.

In actual use, this burner has been found to be extremely efficient and to provide temperatures well above 1500 degrees Fahrenheit without the use of combustion air supplied under pressure, and without the supplying of fuel gas at abnormal pressures. Natural gas is normally furnished at a pressure of 3 to 4 ounces per square inch, and the present invention provides a means of attaining temperatures above 1500 degrees Fahrenheit through the use of such low pressure gas and without requiring the supplemental supply of air under pressure or any other additional equipment. Of course, the burner is also well adapted to use with butane gas under both low and high pressure and for other combustible gases. It is sometimes necessary to adjust the jet cup 38 in accordance with the pressure of various gas supplies, such adjustments being effected by selective positioning of the cup within the bore 37. In general, as the pressure of the gas supply is increased, the cup must be moved away from the chamber D so as to focus the jet of gas flowing from the orifice 40 upon the impingement ring 42.

Of course, it is also desirable to vary the size of the orifice 40 in accordance with the pressure of the fuel gas supply. Normally, this orifice will be formed by a small drill, and it has been found

5 that the range of drills from No. 60 to No. 80, corresponding to an orifice diameter of from 0.0400 inch to 0.0135 inch, will provide for nearly all fuel pressures encountered. As the fuel gas pressure increases, the size of the orifice is reduced. If the variation in the size of the orifice as drilled with consecutive ones of the series of drills is too great, then the adjustment of the cup 38 within the bore 37 is used to trim the flame and provide the desired results. As the fuel gas pressure is increased and the size of the orifice is reduced, the velocity of the gas jet, in general, increases. The nearness of the jet of fuel gas to the primary air inlets 45 governs 10 the amount of air induced to follow along with the gas stream, and therefore as the fuel gas velocity increases, longitudinal adjustment of the cup 38 may be needed to provide a flame of the desired characteristics. This is true because a high velocity jet does not flare as rapidly as one of lower velocity.

15 The use of fuel gases of different heat contents may also necessitate changing or adjustment of the orifice in order to obtain optimum results.

20 The foregoing description of the invention is explanatory thereof and various changes in the size, shape and materials, as well as in the details of the illustrated construction may be made, 25 within the scope of the appended claims, without departing from the spirit of the invention.

25 What I claim and desire to secure by Letters Patent is:

30 1. A gas burner including, a tubular housing forming a mixing chamber and having one end completely open and one end closed, a fuel gas inlet jet in the closed end of the housing for directing a divergent stream of fuel gas into the mixing chamber, the housing having air inlets 35 adjacent the fuel gas jet, an annular impingement shoulder disposed internally in said housing in adjacent spaced relation to its open end, and a finned fuel gas conductor connected to the closed end of said housing in communication with said fuel gas jet and having transverse openings 40 in its fins.

45 2. A gas burner as set forth in claim 1 wherein the fin spaced farthest from the housing is imperforate and all of the fins are disposed substantially at right angles to the longitudinal axis of said housing.

50 ROY M. VARLEY.
